CLAIM

The ornamental design for a tower assembly for power pedestal, as shown and described.

DESCRIPTION

FIG. 1 is a top, front, left side perspective view of a tower assembly for power pedestal, showing our new design;

FIG. 2 is a top, front, right side perspective view thereof;

FIG. 3 is a top, back, right side perspective view thereof;

FIG. 4 is a front elevation view thereof;

FIG. 5 is a back elevation view thereof;

FIG. 6 is a left side elevation view thereof;

FIG. 7 is a right side elevation view thereof;

FIG. 8 is a top plan view thereof; and,

FIG. 9 is a bottom plan view thereof.

The broken lines depict portions of the tower assembly for power pedestal that form no part of the claimed design.

1 Claim, 8 Drawing Sheets
